Roy H. Kluess
Roy C. Finch

UNITED STATES PATENT OFFICE.

ROY H. KLUSS AND RAY C. FINCH, OF SPOKANE, WASHINGTON.

CHARGE-FORMING DEVICE.

Application filed April 10, 1922. Serial No. 551,314.

To all whom it may concern:

Be it known that we, ROY H. KLUSS and RAY C. FINCH, citizens of the United States, residing at Spokane, in Spokane County and State of Washington, have invented certain new and useful Improvements in Charge-Forming Devices, of which the following is a specification.

The present invention relates to improvements in charge forming devices for internal combustion engines, adapted especially for use in automobiles, and particularly pertains to means for varying the volume of gaseous fuel supplied to the engine and adapting the charge to the speed or working condition of the engine. Thus when the engine is idling or not exerting its full power, a minimum quantity or comparatively small supply of fuel is furnished, but when an increased power or speed is required the volume of the fuel gas is automatically increased. By the use of the invention we are enabled to heat a small volume of fuel charge as when the engine is cold or starting, and also are enabled to proportionately heat the larger volume of fuel supplied to the engine when the latter is running at high speed. The volume of gaseous fuel supplied to the engine is controlled by a supply valve, automatically actuated by the volume of gas flowing from the carbureter to the intake manifold, which valve is under the influence of suction from the engine.

In carrying out the invention we utilize, in combination with the carbureter, a plurality of intake manifolds connected with the cylinders of the engine and a supply valve for controlling the flow of gas through the major or larger intake manifold. And the invention consists in certain novel combinations and arrangements of parts herein-after set forth and claimed.

In the accompanying drawings we have illustrated one complete example of the physical embodiment of our invention in which the parts are combined and arranged according to the best mode we have thus far devised for the practical application of the principles of our invention.

Figure 1 is a view in side elevation of the charge forming device.

Figure 2 is a top plan view of the device of Fig. 1.

Figure 3 is a transverse, vertical, sectional view at line 3—3 of Figure 2.

Figure 4 is a vertical longitudinal sectional view at line 4—4 of Figure 3.

Figure 5 is an enlarged vertical sectional view through the supply valve casing and smaller intake manifold.

Figure 6 is an end view, in elevation, of the device of Figure 1.

In order that the assembly and relation of parts may readily be understood we have indicated a portion of an internal combustion engine at 1 in Figure 3, having a usual form of exhaust manifold through which the heated gases of combustion pass from the engine cylinders, and the carbureter is indicated at 3. In the gas pipe 4 of the carbureter a usual throttle valve-lever 5 is shown, above the carbureter, for performing its usual functions.

Above the gas pipe 4 is imposed a cylindrical valve casing 6, which, is provided with a top or head 7 bolted thereto and a check valve 8, of the ball type, is threaded through the top of the valve casing or cylinder.

At the lower end of the valve casing an inlet chamber 9 is fashioned, above which is a tapered or conical valve seat 10 for the hollow valve 11. The valve is cylindrical and is seated by gravity with its conical head 12, that closes its lower end, resting in the valve seat 10 of the valve casing. The open-top, hollow valve is also furnished with small ports or perforations 13 located near its closed lower end, extending transversely through the wall of the valve, and disposed in an annular series around the valve.

At the sides of the valve casing are provided diametrically opposed ports 14, and it will be noted in Figure 5 that the small perforations or ports 13 are located in the valve above the bottom of these ports, in order that suction from the working engine may be exerted on the valve. The larger or main manifold for introducing the fuel charge to the engine comprises a pair of pipes 15 extending laterally from the ports 14 of the valve casing, and having angular nipples 15' that connect with the cylinders of the engine.

An auxiliary or smaller intake manifold is also utilized, which includes a casting box 16, located between the valve casing and main manifold and the exhaust manifold 2 of the engine. This auxiliary intake manifold or hollow casting it will be observed

extends parallel with the main manifold, and the exhaust manifold and lies in close contact therewith, in order that gases passing through the auxiliary manifold may 5 be heated by the hot gases of combustion as they pass through the exhaust manifold. The auxiliary manifold receives fuel gas from the inlet chamber 9 through the port 17 at the center of the auxiliary manifold 10 and the fuel gas passes out of the auxiliary manifold through the nipples 15' to the engine.

In starting the engine or running at low speed, the valve remains on its seat, and 15 the charge passes through chamber 9, port 17 and through the laterally extending auxiliary manifold 16, to the intake ports 15', thence into the engine cylinders in usual manner. While running at comparatively low speed, the fuel charge passing 20 through auxiliary manifold adjacent to the exhaust manifold, is heated by radiation from the exhaust manifold, the volume of gas being positively controlled by the 25 throttle valve and its lever 5. If the speed of the engine is increased by opening the throttle and increasing the volume of fuel gas supplied to the valve, the increased suction resulting from the action of engine 30 results in lifting the automatic supply valve from its seat. The elevated valve permits fuel gas to pass up through the open valve seat in the casing, and the gas now, in addition to passing through the 35 auxiliary manifold, or low speed manifold, also passes through the main or high speed manifold 15. The heated gas from the auxiliary manifold and the comparatively cooler gas from the main or high speed manifold 40 are mixed and pass to the engine cylinders through the nipples 15'. The volume of gas passing through the high speed manifold increases with the ratio of gas permitted to flow past the throttle, and when the 45 throttle is wide open the major portion of the fuel charge passes directly through the main or high speed manifold. If the gases consumed in the engine are not providing the proper efficiency for the engine, the 50 suction from the engine will be decreased. The decreased suction will permit the supply valve to automatically drop to close or partially close the ports 14, thus closing or partially closing the main manifold and 55 causing the fuel gas to pass, in greater volume, through the auxiliary manifold for heating, and in lesser volume through the main manifold. In this matter the supply of gas is automatically maintained in proper condition, and the volume of gas flowing to the engine is automatically governed; the gas is maintained at the proper and desired temperature; and the loss from cold 60 gas is eliminated.

65 The rising and falling movement of the

supply valve, under the influence of suction from the engine, thus maintains the supply of gas in accordance with the requirements of the engine. Air within the valve and valve casing is exhausted therefrom by 70 way of the check valve 8 due to the lifting of the valve under suction from the engine, and this air is also exhausted from the valve and its casing, by suction through the main manifold and perforations or ports 13 in the 75 wall of the casing. The action of the check valve 8 is also instrumental in permitting the supply valve to fall lightly to its seat when suction from the engine is decreased or 80 eliminated.

It is known in practice that the heavier gases, the more moist gases and the gas that is inefficiently mixed with air will travel 85 along the outside walls of the manifold pipe while the lighter gases will follow through the center or channel. It is my purpose that these lighter gases when the engine is working under load will be received directly into the cold manifold and 90 that the heavier gases or those carrying moisture or drops of fuel will be automatically separated, or rather directed into and through the auxiliary manifold where it will be vaporized before passing into the motor. This is accomplished by having the opening 95 in the conical valve seat 10 smaller in area than that of the manifold pipe, or carbureter outlet, the heavier gases thus striking against the outside of the valve seat and being deflected and passed through the auxiliary manifold port 17 and thus through the laterally extended manifold 16 to the intake ports 15', the result being that all particles 100 of fuel received in the engine will be in a high state of combustion and evenly mixed.

In case raw fuel, that is fuel in a liquid state should pass through the main manifold it would be trapped before entering the engine by being received into the auxiliary manifold, for as it flows through the manifold 15 it will pass and be received into the auxiliary manifold 16 as this manifold while extremely narrow is enlarged in area over that of 15 at the point of passage and the 110 gas will flow into 16 and be vaporized 115 through the action of the heat in this member.

From the above description taken in connection with our drawings it will be apparent that we have designed an automatic supply device, or charge forming device which fulfills the purposes and objects heretofore set forth, and which performs its 120 functions in an efficient and reliable manner.

Having thus fully described our invention, what we claim as new and desire to secure by Letters Patent is:

The combination with an internal combustion engine including its gas pipe, carbureter, throttle valve and exhaust manifold,

- of a cylindrical valve-casing connected with the gas pipe, a main manifold comprising downwardly inclined pipes from said casing connecting said casing and engine, an automatic supply valve comprising a cylinder having a closed bottom and perforated side walls, an exterior auxiliary manifold adjacent to the exhaust manifold and communicating with the casing below said valve, and said auxiliary manifold communicating with the main manifold between the engine and casing.
- 5 In testimony whereof we affix our signatures.
